The ornamental design for a spray nozzle attachment for a pressurized aerosol can, as shown and described.

DESCRIPTION

FIG. 1 is a right end view of a spray nozzle attachment for a pressurized aerosol can showing our new design;

FIG. 2 is a left end view thereof;

FIG. 3 is a front elevational view thereof;

FIG. 4 is a rear elevational view thereof;

FIG. 5 is a top plan view thereof; and,

FIG. 6 is a bottom plan view thereof.
